UNITED STATES PATENT OFFICE.

JOHN THOMAS MEYER, OF MINSTER, OHIO.

SPOON.

1,144,490.

Specification of Letters Patent. Patented June 29, 1915.

Application filed August 26, 1914. Serial No. 858,695.

To all whom it may concern:

Be it known that I, JOHN THOMAS MEYER, a citizen of the United States, residing at Minster, in the county of Auglaize and

5 State of Ohio, have invented certain new and useful Improvements in Spoons, of which the following is a specification, reference being had to the accompanying drawings.

10 My invention relates to certain new and useful improvements in spoons, and especially to that type desirable in blessing baptismal water in the Catholic Church.

It has always been found difficult to pour 15 the holy oils from a tin bottle into the water and at the same time read the necessary prayers from a book, and it not infrequently happens that either too much oil or none at all is poured.

20 A still further difficulty occurs when two oils must be poured simultaneously so that they may mix and flow in one stream into the water.

I have recited these conditions to accentuate 25 the fact that my invention has for its object to provide a spoon adapted to simplify the operations referred to.

With this end in view my invention consists in the peculiar construction hereinafter 30 more fully set forth and illustrated in the drawing.

In order that those familiar with the operation of blessing baptismal water may fully appreciate my invention and its advantages I will now proceed to describe the same referring by numerals to the accompanying drawing in which—

35 Figure 1 is a top or plan view of a spoon embodying the features of my invention, Fig. 2 is a longitudinal section on the line $a-a$ of Fig. 1, and Fig. 3 is a transverse section on the line $b-b$ of Fig. 1.

Similar reference numerals indicate like parts in the several figures of the drawing. 40 1 is the bowl and 2, the handle of the spoon. The bowl at its upper edge is formed with two lateral centrally disposed pouring lips 3, 3, and with a lip 4 at the extreme point.

The wall of the spoon converges toward 50 the bottom as clearly shown, and the bottom is flat in order that the spoon may rest upon any suitable support when desired.

A longitudinal partition 5, divides the spoon into two compartments 6 and 7 of 55 equal area, and the walls of this partition at each end are flared slightly in an outward and downward direction and at the front end they converge as clearly shown at 8 in Fig. 1, and terminate centrally of the lip 4, 60 and they are slightly concave midway of their extremities as shown at 9, 9. The concavities 9 are for the purpose of preventing any chance of the oil contained in the bottom of one of the compartments from running over or around the pointed end of the partition 5 and so getting over into the other compartment when the spoon is tipped laterally.

From the construction shown it will be 70 seen that the two oils may be poured into the two compartments 6 and 7 of the spoon instead of directly into the water, and that when the occasion arises for pouring the two oils simultaneously into the water it is 75 only necessary to tilt the spoon in the direction of the lip 4, and that the partition 5 will naturally direct the oils each side thereof to flow equally to and out from the lip 4, thus avoiding the exercise of special 80 care or judgment.

While my improved spoon is especially designed for use by the Catholic clergy it will be understood that it may be very desirable for other purposes.

85 What I claim as new and desire to secure by Letters Patent, is:—

1. A spoon of the character described, having a bowl, the bowl being provided with a pouring lip at each side and a pouring lip at the point of the spoon, and a central longitudinally extending partition dividing the bowl into two equal compartments, said partition terminating short of the lip at the point of the bowl and said 90 partition being formed on each side with a concavity whereby to permit collection of the liquid on one side of the spoon in said

concavity when the liquid on the other side of the spoon is being poured from the corresponding lateral lip.

2. In a duplex compartment spoon provided with two lateral pouring lips and a pouring lip at the point and with a central longitudinal partition converging at its forward end and terminating centrally of the lip at the point, said partition at each end

flaring outwardly toward the bottom of the spoon and with a central concavity on each side substantially as set forth.

In testimony whereof I hereunto affix my signature in the presence of two witnesses.

JOHN THOMAS MEYER.

Witnesses:

FRANK SCHUMECKER,

LAURENCE STEINEMANN.
